UNITED STATES PATENT OFFICE.

JAMES W. WINFREY, OF ASHDOWN, ARKANSAS.

HEATING DEVICE FOR OIL-PRESSES.

No. 809,547.

Specification of Letters Patent.

Patented Jan. 9, 1906.

Application filed May 11, 1905. Serial No. 260,001.

To all whom it may concern:

Be it known that I, JAMES W. WINFREY, a citizen of the United States, residing at Ashdown, in the county of Little River and State of Arkansas, have invented a new and useful Heating Device for Oil-Presses, of which the following is a specification.

This invention relates to presses of that general class employed for expressing oil from cotton seed, linseed, and the like, and has for its principal object to improve the construction of the press in such manner as to materially increase the yield of oil, especially when starting up after the press has been idle for some time.

It is found in practice that after shutting down on Saturday night and again starting to work on Monday the press is cold, the mass of metal, and especially the head-block, being thoroughly chilled, and during the first pressing operations this materially interferes with the free flow of oil, especially from the bags in contact with the head-block, and it is not until the press becomes heated that the full yield of oil is obtained.

The object of the present invention is to prevent this waste by heating the head-block in order to increase the temperature of the same to a point where the flow of oil will not be retarded, it being found that the oil exudes more rapidly from a heated press than from one that has been cooled off by exposure.

The accompanying drawing illustrates an oil-press constructed in accordance with the invention, the head-block of the press being shown in section.

The base, plunger-block A, pillars B, and head-block 10 are connected in the usual manner, and suitable means are employed for forcing the plunger upward to compress the material being treated.

In ordinary presses the head-block is usu-

ally formed of a mass of iron in the form of a solid block, which if thoroughly chilled will 45 reduce the temperature of the material with which it is in contact, and thus impede the flow of oil. In the present case the head-block 10 is hollow and is preferably provided with a plurality of diagonally arranged 50 strengthening-ribs 11 to brace the central portion of the lower face of the block. To the upper portion of the block is connected a steam-supply pipe 12, having a reducing-valve 13 and a controlling-valve 14, so that 55 steam under any desired pressure and in any desired quantity may be admitted to the hollow head-block, the waste steam and water of condensation passing off through a valved exhaust-pipe 15.

The heated block is found in practice to materially increase the yield of oil and to prevent injury to the press-clothes, the heated block preventing clinging of the cloth thereto.

Having thus described the invention, what is claimed is—

An oil-press having a hollow head-block, and a plurality of strengthening-ribs arranged within the interior of the block for bracing the lower central portion of the latter, said 70 ribs being inclined upward from the central portion toward the outer edges of said block, a steam-supply pipe entering the upper portion of the hollow head, and an exhaust-pipe leading from the lower portion of said head, 75 the supply-pipe being provided with a reducing-valve for governing the quantity of steam admitted to said head.

In testimony that I claim the foregoing as my own I have hereto affixed my signature 80 in the presence of two witnesses.

JAMES W. WINFREY.
